CEILING CONSTRUCTION

Roger H. Stitt, Chicago, Ill., assignor to United States Gypsum Company, Chicago, Ill., a corporation of Illinois

Application February 16, 1945, Serial No. 578,243

6 Claims. (Cl. 72—118)

1

This invention relates generally to a building construction but has special reference to a ceiling or the like comprising panels provided with a kerf in the edges thereof, for example, tile used for constructing a ceiling having acoustic corrective qualities.

In the erection of ceilings of the type mentioned, the general practice is to utilize tiles of, say, 12" x 12" or 12" x 24" in size, and to assemble them in edgewise abutting relation, the tiles nearest the walls being rough cut when necessary to complete the entire area to be covered. Inasmuch as several different modes of supporting these tiles are in use and a number of them employ a member of some kind engaging adjoining kerfs of a pair of abutting panels, the latter are furnished by most suppliers with a kerf in each edge of the relatively thin flat panel.

However, means heretofore available for supporting ceilings of this type are such as to render the installation permanent, whereas it is frequently desired that the ceiling be removable in part for access thereabove. For example, it may be necessary to install or repair piping between the ceiling and the floor above, and such work is greatly facilitated and lowered in cost if the panelled ceiling and its supports are so arranged that a panel or panels may be quickly and easily removed without destroying or damaging any thereof.

Present methods of installation utilize spline members interengaging kerfs of abutting panels and having permanently fastened clips to secure the splines to the ceiling supporting framework, and with that type of construction it is impossible to remove a panel without rendering the same unfit for reinstallation.

With these prior practices in view the principal object of the invention is to provide means for supporting a ceiling comprising abutting tiles adapted to permit a panel or panels, after once being erected, to be removed without damage thereto or the adjoining panels and, when the purpose for which the panel has been removed is accomplished, to permit the same to be easily and cheaply reinstalled.

Another object is to provide means for suspending a ceiling in the manner outlined utilizing a novel type of spline and clip interengaging therewith, the clip being adapted to be hung from suitable runners supported from the floor above.

Still another object is to provide in a suspension means for a ceiling a spline and clip so co-operating that the clip may be manually moved with

2

respect to the spline to disengage the clip from its supporting member.

A further object is to provide a clip as aforesaid so adapted and arranged that it may not become accidentally dislodged from its supporting member while still permitting manual disengagement thereof from the same.

Still another object is to provide in a suspended ceiling construction spline members of one kind interengaging adjacent kerfs of the ceiling panels extending in one direction and with which the clips are adapted to co-operate; and splines of another kind engaging the adjacent kerfs running in a direction at right angles to the other, the two types of splines being so adapted and arranged as to permit the removal of a ceiling panel and then its reinstallation using the same splines.

Still further object is to provide at the margins of a suspended ceiling of the type mentioned supporting members attached to the walls and adapted to receive the marginal edges of the border panels, and resilient means interposed between the edges of the panels and the supporting member which in the normal use of the ceiling serve to retain the several panels in closely abutting relation but which, when a panel is to be removed, may yield to permit separation of the panels.

Another object is to provide a resilient member as aforesaid which comprises a one-piece element of cheap, simple construction easily installed without the use of tools.

Other and further objects will appear as the description proceeds.

In carrying out the invention in one form I provide a plurality of splines having an inverted substantially T-shaped cross section, the stem of the T including a groove longitudinally of the spline and the two halves of the head of the T being adapted to engage adjoining kerfs of a pair of abutting panels. Adapted to co-operate with the spline by sliding thereon is a hanger member or clip having a vertically disposed web the bottom of which is formed to provide a pair of opposed flanges extending laterally from both sides of the web. In order to adapt the clip for sliding upon the spline member the web is first bent outwardly at right angles to itself to form a flange and then returned upon the flange and extended beyond the web in the opposite direction. Sufficient clearance is left between the first mentioned flange and the returned portion to provide a slot which may engage one laterally extending flange of the spline.

The web of the clip is provided with a substan-

substantially rectangular notch extending inwardly from one vertical edge thereof, the notch being of sufficient height to engage freely a runner constituting part of the supporting structure. Furthermore, the notch is provided near its outer or open end with a projection extending inwardly thereof and adapted to contact the runner when the clip is moved thereon to prevent unpremeditated dislodgement of the clip. The lower edge of the notch is chamfered in a manner as to permit the clip to be raised vertically to clear the runner and thus allow the projection aforesaid to be lifted free of the runner for total disengagement of the clip therefrom.

The runners may be supported in any convenient manner from the floor above and in the form of the invention to be described I have shown purlins spaced at convenient intervals and suitably supported from the floor above, and to which a plurality of runners may be wired or otherwise attached.

For engaging the abutting panels along their lines of junction which are at right angles to the T-shaped splines hereinabove mentioned, I provide a plurality of thin flat splines to engage adjoining kerfs and removable by endwise sliding thereof.

For permitting the shifting of a panel laterally in order to disengage the splines I provide at the edge of each panel where it meets the wall at least one resilient member which, in the normal use of the ceiling serves to thrust the panels of a row one against the other and maintain the required close contact therebetween. These resilient members may be supported in a channel fastened to the wall and between the flanges of which is inserted the edges of those panels associated with that wall.

In the drawings:

Fig. 1 is a perspective view of a portion of a ceiling constructed according to my invention and looking downwardly thereon;

Fig. 2 is a partial view on enlarged scale showing a corner of one panel, the two types of splines, a clip, and a runner;

Fig. 3 is a perspective view of one of the clips;

Fig. 4 is an enlarged view of a section of a panel, of a wall channel and of one of the resilient members in assembled relation.

Fig. 5 is a perspective view of one of the resilient members;

Fig. 6 is a view showing one step in the process of disengaging a clip from its runner;

Fig. 7 shows an intermediate step in that process;

Fig. 8 shows the final step in that process;

Fig. 9 is a view in the opposite direction of those of Figs. 6, 7 and 8 indicating the process of removal of a clip; and

Fig. 10 is a perspective view looking upwardly toward the ceiling showing several of the panels in process of removal.

In some of the figures parts have been broken away for clarity.

Referring first to Fig. 1, the ceiling is shown comprised of individual panels 10, for example, 12" x 24" in size, each being provided with an edgewise kerf 11 along the two shorter edges and a like edgewise kerf 12 along the two longer edges (Fig. 2). As is usual in modern ceiling tiles, that portion of the edges thereof above the kerf 11 or 12 is rabbeted slightly as indicated at 13 and for a purpose which will appear. Interengaging adjoining kerfs 12 of a pair of panels 10 are the splines 14 of inverted substantially

T-shaped cross section and formed in this instance of a single thin sheet of metal in such manner as to result in a stem for the T of condensed inverted V-form 15 as most clearly seen in Fig. 9, the narrow opening formed within the V being indicated by the reference numeral 16. The head of the T is constituted by the two lateral oppositely extending flanges 11 adapted to engage the adjoining kerfs 12. For rigidity consistent with convenience of assembly and disassembly the splines 14 may be made longer than a single panel and in this case they are each indicated as being the length of two panels or 48" (Fig. 10).

Adapted to engage the T splines are the clips 21 also being formed of a single piece of thin flat material to include a web or skirt 22, a flange 23 and a flange 24. The flanges 23 and 24 are constituted by deforming the sheet at right angles to the web 22 and extending it laterally a predetermined distance to form the web 23 and then returning it upon itself to a point beyond the web 22 to form the flange 24. When returning the metal to form the flange 24 an opening 25 is left between the flanges 23 and 24 whereby the clip may be engaged over the flanges of a spline 14 as seen in Fig. 9. The total thickness of a flange 17, together with the metal comprising the flanges 23 and 24 and the clearances therebetween is slightly less than the width of the kerf 12, and the opening 25 is slightly greater in height than the thickness of the metal comprising the flange 17, the desideratum being that the clip 21 may be moved with only slight friction longitudinally upon the spline 14 and within the kerf 12. It will be apprehended that the rabbets 13 are sufficiently deep to permit the proper clearance for reception of the spline 14 and clip 21 and the free movement of both for disengagement of a panel or panels in a manner to be detailed hereinafter.

The number of clips individual to a single spline 14 will be dependent upon the physical dimensions of the ceiling panels and their weight. In the present instance I have shown three such clips associated with each spline section 14, there being one centrally thereof, and one at each end, the end units bridging over two abutting T-splines.

Disposed above the panels 10 is the plurality of runners 31 which may be of any suitable cross section but in this case are shown as light weight channels, for example, plasterers' channels, there being one such runner to support the plurality of clips aligned transversely of the splines 14. The runners 31 may be supported in any suitable manner but in this case are shown as being wired as at 32 to purlins 33 which are suspended as by hangers 34 to the floor above. The number and spacing of the purlins 33 constitutes no part of the invention, these characteristics being dictated by good design in order to carry properly their suspended load.

To engage the runners 31 each clip (Fig. 6) is provided in its web 22 with a substantially rectangular notch 35, the width of the notch measured in a vertical direction being sufficient to fit snugly over the flanges of a runner 31 (Fig. 2) but free to slide thereon either transversely or longitudinally thereof. At its open end the upper edge of the notch is extended slightly inwardly of the notch in a nose or projection 36 having its inner margin sloping slightly at 37 as shown. Substantially below the projection 36 the opposite corner of the notch is cham-

ferred as at 38 to provide a mouth or throat for the notch 35, the nose 36 lying within said mouth for a purpose to be described.

To provide mutual support between the narrower abutting edges of the panels 10 and to insure a tighter seal therebetween there is provided a plurality of flat splines 41 extending between rows of splines 14 and fitting within the kerfs 11. Preferably one end of each spline 41 is adapted to overlap a flange 17 as shown in Figs. 2 and 9, the opposite end merely abutting the closed or bend edge of the flange 23. Thus the splines 41 are substantially supported on the splines 14 and thereby increase the strength of the framework carrying the ceiling panels 10. Moreover by so overlapping a spline 41 with a flange 17 levelling of the panels 10 and their alignment in the same plane is properly attained.

To support the ceiling marginally there may be attached to the walls 44 (Figs. 1 and 4) the channels 45, the web 46 thereof being affixed to the wall by any well-known means, e. g., screws. The flanges 47 are spaced sufficiently far apart to receive the thickness of a panel 10 for free sliding movement transversely and longitudinally with respect thereto.

Where they are received between the flanges 47 the edges of the panels 10 are rough cut short of the web 46 a predetermined distance to permit the insertion of resilient elements 51, the cut-off being just sufficient to enable an element 51 to be held in position laterally against accidental shifting but to permit the element to be compressed when a panel 10 is moved outwardly.

Referring particularly to Fig. 5 it will be noted that the element 51 comprises a single piece of resilient metal having a body portion 52 adapted to abut an edge of a panel 10 and two wings 53 extending outwardly therefrom at an obtuse angle, the wings 53 terminating in curled extremities 54. As an element 51 is compressed by outward movement of a panel 10 the wings 53 will yield with respect to the body 52, the curled ends 54 permitting the two ends of the element to slide freely upon the surface of the web 46.

Installation of a ceiling in accordance with my invention may be accomplished in any of several ways. For illustration and assuming that the purlins 33, runners 31 and wall channels 45 are in place, I can begin by first placing elements 51 within the flanges 47 and then positioning a first panel 10a within the flanges (Fig. 1). I can then insert the next panel 10b together with its element 51. Following this I insert a spline 41 and a spline 14 which latter, as mentioned, may be of sufficient length to encompass the panels 10a and 10b, the spline 14 having first been assembled with two clips 21a and 21b, and these are simultaneously engaged with the runners 31. Although not essential, I have shown the two runners 31 of Fig. 1 in alignment with lines of junction of the panels. It will be apparent from a consideration of the invention that the runners may be positioned otherwise than as shown, considered lengthwise of splines 14.

I may then continue the installation by inserting panels 10c and 10d in a similar manner and continue thus throughout the entire ceiling. When an opposite wall is reached the border sections may be inserted toward the other wall against the resilience of the elements 51 to allow sufficient clearance for thrusting the last or marginal panel 10 upwardly into place between the flanges 47 whereupon the pressure may be re-

leased and the elements 51 will restore the panels so that the entire ceiling is properly centered by the opposing elements 51 at either margin and supported within the wall channels 45. Since the clips 21 are slideable longitudinally of the runners 31 it is apparent that the entire ceiling is shiftable laterally in either direction the amount permitted by an element 51.

Now if it is desired to remove a ceiling panel or panels I can proceed as indicated in Figs. 6 through 10. First referring to Fig. 6, a knife blade 60 is inserted between a pair of abutting panels 10 and within the groove 16 and is pressed against the end of the flange 24. This action will slide the clip 21 to the left as seen in Fig. 7 until the projection 36 strikes the upper flange of the runner 31. At this point the chamfer 38 will open sufficient space between itself and the corner of the runner 31 nearest thereto to permit the ceiling panels associated with the clip 21 as well as the clip to be lifted upwardly by manual pressure until the projection 36 may be cleared over the upper flange of the runner 31. Pressure on the blade 60 is meanwhile continued in the same direction until the clip is entirely clear of the runner 31 as shown in Fig. 8. The operation just outlined is performed on the other two clips associated with a spline 14. The clips now having been cleared from the runners 31, four panels 10 are free to drop downwardly. Now a knife blade may be inserted in a joint associated with the splines 41 and panels adjacent to those to be removed, for example, 10e, 10f, 10g and 10h (Fig. 10) may be moved toward the walls and against the resilient elements 51 to free the said panels from engagement with their associated splines 41.

Now the panels 10 to be removed may be dropped downwardly until the stem 15 of the spline 14 is cleared below the bottom of the ceiling whereupon it may be grasped with a pliers and withdrawn endwise from the kerfs 12. Now that the panels 10 have been separated from the intermediate spline 14 they may be removed entirely.

For reinstallation of the panels the procedure just outlined is reversed except that the knife blade 60 would be inserted against the opposite end of the flange 24.

Inasmuch as there is no rigid attachment between the ceiling panels 10, the runners 31 and wall channels 45, the ceiling is suspended in the full sense of the term and free to move in all directions under the various conditions which may produce changes in the position thereof or of its component panels. Thus by relieving strains resulting from such changes the danger of distortion or fracture of a panel is completely eliminated.

Because there is no rigid connection between the panels and the supporting structure, the latter likewise is free to move without transferring stresses to the panels proper.

By virtue of the resilient elements 51 the tiles are at all times thrust together in closely abutting relation to result in tight joints and the avoidance of drafts and dust transmission therethrough.

It will be understood that the splines 14 are preferably arranged with their joints in staggered relation thus providing greater rigidity to the supporting structure. For convenience in describing the invention I have indicated that the joints of the splines 14 may be in alignment.

To my knowledge present systems have no provision at the rough cut border tiles to prevent

lateral shifting thereof so that those tiles are free to move and permit undesirable cracks to be opened. By the use of the element 51 every joint is maintained in snugly abutting relation.

While I have shown particular embodiments of my invention, it will be understood, of course, that I do not wish to be limited thereto since many modifications may be made, and I, therefore, contemplate by the appended claims to cover any such modifications as fall within the true spirit and scope of my invention.

Having thus described my invention, what I claim and desire to secure by Letters Patent is:

1. A supporting assembly for a ceiling comprising kerfed edge abutting panels including in combination an elongated spline member coextensive with the abutting edges of at least two panels, said member having a downwardly opening longitudinal groove substantially in alignment with the line of junction of said two panels and oppositely extending longitudinal flanges adapted to enter the juxtaposed kerfs, a plurality of hangers associated with said member, each said hanger including a vertically disposed web having a substantially rectangular notch in one vertical edge thereof, the upper edge of said notch being provided near its open end with a portion extending into said notch and said notch being wider at the region of said extending portion and said hanger including a flange adapted to underlie said first mentioned flanges and to lie within said juxtaposed kerfs, and a plurality of supporting members disposed above said panels and adapted to engage said notch, the upper margin of each notch overlying a supporting member, and said hanger being transversely slidable with respect to its associated member.

2. A supporting assembly for a ceiling comprising kerfed edge abutting panels including in combination an elongated spline member coextensive with the abutting edges of at least two panels, said member having a downwardly opening longitudinal groove substantially in alignment with the line of junction of said two panels and oppositely extending longitudinal flanges adapted to enter the juxtaposed kerfs, a plurality of supporting members disposed above said panels, a plurality of hangers associated with said spline member, each said hanger including a vertically disposed web having a substantially rectangular notch in one vertical edge thereof, the upper edge of said notch being provided near its open end with a projection extending into said notch and the lower edge of said notch having its outer corner chamfered, the distance from the outermost extremity of the chamfer to the lower edge of the notch being greater than the distance from the upper edge of the notch to the lower end of said projection, both distances being measured vertically, and the distance from the inner edge of said projection to the innermost extremity of the chamfer measured horizontally being at least equal to or wider than the horizontal width of a said supporting member, and said hanger having a flange adapted to underlie said first mentioned flanges and to lie within said juxtaposed kerfs.

3. In a building construction, a plurality of abutting units adapted to form a suspended surface structure, each said unit having a kerf in each of at least two opposed edges thereof, a plurality of supporting members disposed above said units, a plurality of splines of inverted T-shaped cross section disposed normally to said supporting members the horizontally extending parts of the head of the T entering adjacent kerfs

of adjoining panels and the leg of the T being disposed vertically, and a plurality of members interconnecting said splines and said supporting members, said interconnecting members including a portion to engage the head of the T and a hooked portion to transversely engage said supporting members, the notch of said hook forming a snug, sliding fit with respect to said supporting members at their region of engagement, said notch being wider at its open end and having the nose of the hook adjacent said wider part and overhanging one side of said member, said hooked portion overlying the top of the supporting member and removable therefrom when said interconnecting member is moved from engaging position, and the panels and splines being spaced sufficiently below said supporting members to permit said panels and splines to be manually lifted for disengagement of the nose of the hook from the supporting member when the wider portion of the notch is moved to a position vertically coincident with a supporting member.

4. In a building construction, a plurality of abutting units adapted to form a suspended surface structure, each said unit having a kerf in each of at least two opposed edges thereof, a plurality of supporting members disposed above said units, a plurality of longitudinally slotted, laterally flanged elements disposed normally to said supporting members, the flanges of said elements being adapted to enter adjacent kerfs of adjoining panels, and a plurality of members interconnecting said elements and said supporting members, said interconnecting members including a portion to engage said element and extend over said slot, and a hooked portion to transversely engage said supporting members, the notch of said hook forming a snug, sliding fit with respect to said supporting members at their region of engagement, said notch being wider at its open end and having the nose of the hook adjacent said wider part and overhanging one side of said member, said hooked portion overlying the top of the supporting member with which it is engaged and removable therefrom when said interconnecting member is moved from engaging position, and the panels and elements being spaced sufficiently below said supporting members to permit said panels and elements to be manually lifted for disengagement of the nose of the hook from the supporting member when the wider portion of the notch is moved to a position vertically coincident with a supporting member.

5. A supporting assembly for a ceiling comprising abutting panels having kerfed edges comprising in combination a spline member having a substantially central downwardly opening groove and oppositely extending flanges adapted to engage the kerfs of abutting panels, a fixed supporting member above said panels, a hanger including a portion to slidably engage said flanges and a substantially centrally disposed upward extension having a horizontally disposed notch positioned above the upper face of said panels, the top margin of said notch resting upon the top face of said supporting member and said hanger being transversely slidable with respect to said member, said notch including a rectangular part having a vertical width sufficient to slidably and snugly engage over said supporting member, a tapered mouth having a downward projection extending into said mouth whereby when said hanger is fully engaged over said supporting member the rectangular part prevents vertical

shifting of said hanger, but upon transverse sliding of said hanger with respect to said supporting member said mouth will permit upward shifting of said hanger to disengage the projection from the member and to complete disengagement of the hanger from the member. 5

6. In a ceiling construction a plurality of abutted panels, sets of members interposed between the edges of adjoining panels adapted normally to maintain said panels in flush relation 10 but to permit manual lateral separation of adjacent panels, second sets of supporting members disposed above the ceiling, elements intermediate said two sets of members to support the ceiling panels over the major extent thereof, a third set 15 of ceiling supporting members embracing the ceiling at the margin thereof, a space being formed between said margin and the bases of said third set of members, and resilient elements intermediate said margin and said third set of mem- 20

bers, and disposed in said space, said space being unobstructed for at least a distance equal to half the width of a member of said first set of members whereby disengagement of a panel from the member may be effected.
